UNITED STATES PATENT OFFICE

JAMES P. BURKE, OF NEWARK, NEW JERSEY, ASSIGNOR TO MACK MOLDING COMPANY,
OF LITTLE FALLS, NEW JERSEY, A CORPORATION OF NEW JERSEY

DESIGN FOR A CONTAINER CAP

Application filed March 1, 1929. Serial No. 30,273. Term of patent 7 years.

To all whom it may concern:

Be it known that I, JAMES P. BURKE, a citizen of the United States, residing in Newark, in the county of Essex and State of New Jersey, have invented a certain new, original, and ornamental Design for Container Caps, of which the following is a specification, reference being had to the accompanying drawings, forming a part thereof, and of which—

Figure 1 is a top plan view; Fig. 2 is a vertical section of the top portion of the container cap taken on the line 2—2 of Fig. 1, and Fig. 3 is a view in side elevation of a container cap showing my new design.

I claim:

The ornamental design for a container cap as shown.

JAMES P. BURKE.
